CASING REMOVING INSTRUMENT

Virgil C. Applegate, Denver, Colo.

Application June 14, 1946, Serial No. 676,739

1 Claim. (Cl. 30—355)

1

This invention relates to instruments for removing the casings surrounding certain substances such as the "Visking" skins in which frankfurter and wiener meat are encased during manufacture and thus make these meat products into what is termed in the trade as "skinless."

One of the objects of my invention is to produce a casing removing instrument of the type referred to which can be easily and efficiently handled by the operator so as to quickly and smoothly remove the casings or skins from substances such as frankfurters or wieners.

Another object is to so construct an instrument of the kind referred to, and particularly the blade thereof, that the operator, by employing a minimum of manipulations, can "skin" a meat product without marring the meat.

A further object is to so construct and embody in a casing removing instrument for use in "skinning" frankfurters and wieners, a narrow and thin, toothed blade which can be quickly and efficiently used to cut off a link and then remove the casing or skin.

Other objects of my invention will become apparent from the following description taken in connection with the accompanying drawings in which:

Figure 1 is a side view of a casing removing instrument embodying my invention;

Figure 2 is a sectional view taken on the line 2—2 of Figure 1 showing the attaching means for the blade; and

Figure 3 is a view showing a different blade construction.

Referring to the drawings in detail and first to Figures 1 and 2, a preferred form of my casing removing instrument is shown thereby which comprises a handle H and a blade B. The handle is approximately four to five inches in length, approximately three-fourths inch wide and about one-fourth inch thick so that the handle will be of a proper size to permit the operator to grip it firmly in the complete palm of his or her hand with the forefinger and thumb grasping the handle closely adjacent the end from which the blade extends. The handle is provided with a longitudinal kerf or slot 1 which extends about three-fourths of the distance through the width of the handle and positioned in this slot is the rear end portion of the blade B. The blade is held clamped in the kerf by means of a bolt 2 extending through an opening 3 in the blade. The head of the bolt is slotted to permit it being turned by a screw driver and both the head and the nut 4 are counter-sunk into the side of the handle so

that the handle will be smooth. The portion of the blade which is clamped in the slot by the bolt is arranged to have its back edge engage the bottom of the slot so that with this arrangement, together with the clamping action, the blade will be firmly held against any relative movement.

An important feature of the invention embodied in the instrument resides in the blade which is so constructed as to have approximately between one inch and one and one-fourth inches of length extending from the handle. The outer extending end portion 5 of this blade, comprising at least one-third of the length of the blade, is of considerably narrower width than the major width 6 of the blade, it being not more than approximately one-fourth of an inch in width. The extreme outer top edge of this narrow end portion 5 is curved as indicated at 7. The operating edge of the blade is constructed to be provided with teeth 8 and these teeth should be of such size that their number is between substantially eighteen teeth to twenty-four teeth to the inch. The teeth are formed to be provided with an inclination on their rear edge, that is, the edge towards the handle and the forward edge of the teeth are so arranged as to give the teeth a forward rake. The curved edge 7 at the end of the narrow portion of the blade is arranged to meet the outer end tooth in such a manner that this tooth provides an end piercing and pickup point at the outer end of the operating edge of the blade which permits the blade to be effectively used during skinning operation. The teeth also may be provided with a set if desired, that is, alternately bent to the sides of a medial line. The entire back edge of the blade is flat to prevent injury to the operator.

In using my improved casing removing instrument the blade is first employed to operate on the linking portion or joint between adjacent frankfurters or wieners resulting from the process of manufacture, the meat thereof being encased in suitable casing or skin such as "Visking." The blade is inserted at the joint and the links cut in two by the use of the teeth on the blade. The cutting is done by moving the teeth of the blade toward the face of the thumb with the joint portion in between. After cutting off a link the teeth of the instrument, particularly the outer end tooth, are employed to pick up the skin. The thumb is then slid up on the blade so as to clamp the skin between the thumb and the teeth of the blade and then the skin given a peeling action, thereby removing at least a part of it from the wiener or frankfurter. With this part of the

skin removed it is an easy matter then to use the teeth of the blade, together with the thumb to pick up additional skin and remove it until all of the skin is removed. By having the teeth small and of the order specified the skin can be quickly picked up and peeled off, yet there will be very little danger of marring or scarring the frankfurter or wiener. The shortness of the blade also permits the thumb to be easily slide to the outer end to cooperate with any of the teeth during picking up and peeling of the skin.

The particular construction of the blade, especially its length and the relatively narrow outer end, permits the blade to be easily and efficiently inserted at the joint between two linked frankfurters or wieners to perform any necessary piercing and twisting operation, together with the "pickup" of the skin. If the blade were wider at the end, then easy twisting of the blade would be interfered with. The end of the blade, however, is wide enough so as to permit sufficient engagement of the thumb with the teeth so as to clamp a marginal portion of the skin to accomplish the peeling action. By having the portion of the blade closest to the handle of greater thickness than the outer end portion, considerable strength will be added to the blade which insures remote possibility of breakage and attendant long life. This wide portion also insures that there will be a greater area to be engaged by the thumb during the skinning operation after the skin has been picked up.

The skinning of frankfurters and wieners is usually done by the use of ordinary paring knives. Actual use by experienced operators in meat packing plants has shown that the same operator can, by the use of my improved casing removing instrument, increase his or her output as much as fifty percent over the output by the use of a paring knife. There also has been some use of a "skinning" instrument in which an ordinary paring knife blade is provided with teeth instead of a smooth sharp edge. This instrument is slightly more efficient than the ordinary paring knife, but even in comparison with such instrument my improved instrument is still capable of increasing the output of the operator between thirty and forty percent. This increased output, with the use of my improved instrument, is believed to result primarily from the particular size and shape of the blade, the size, shape and arrangement of the teeth and the general ease and rapidity of the manipulation of the instrument, due to its balance and proper hand gripping size. The narrow end portion of the blade permits very quick and easy piercing of the skin and initial peeling. It has been clearly demonstrated that ordinary knives having ordinary blades, even though provided with saw teeth, completely fail to give the efficient and startling results accomplished by my improved instrument, thus proving that a definite forward step has been accomplished by the particular casing removing instrument shown and described.

In Figure 3 a slightly modified instrument is disclosed, differing essentially from that shown in Figure 1 by the shape of the blade. The instrument shown in Figure 3 is primarily designed for use of blade material not requiring additional strengthening adjacent the handle. In this Figure 3 instrument the handle H' is provided with the slot 1 into which the blade B' is clamped by the bolt 2. The width of the blade portion

which is clamped in the handle is considerably greater than the width of the blade portion 9 which extends from the handle. This portion 9, as disclosed, is of uniform width being substantially the same width as the end portion 5 of the instrument shown in Figure 1. Its length is approximately between one inch and one and one-fourth inches. The end edge of the blade is provided with a top rounded corner 10 and the lower edge of the blade is provided with teeth 8' of the same general shape and size as the teeth 8 of the instrument in Figure 1.

The instrument in Figure 3 is operated in the same manner as the instrument in Figure 1. 15 The end portion of the short blade 9 can be easily inserted at the joint between two frankfurters or wieners to sever the joint and the teeth employed to pick up the skin for the skinning operation.

20 Both casing removing instruments shown by way of example as embodying my invention may have their handles made of wood, but other material can be used such as plastic. The particular arrangement of attaching the handle to the 25 blade permits the blade to be removed at will so that in the event the blade should become broken a new blade can be quickly substituted therefor without purchasing an entirely new instrument. The attaching arrangement of the handle to the 30 blade always insures that the blade will be firmly clamped in the handle with no relative movement permitted. Besides the particular cooperation between the slot and the blade which will prevent shifting of the blade, the clamping action 35 of the parts of the handle at opposite sides of the slot on the teeth of the portion of the blade which fits into the slot will also aid in making a firm attachment.

Being aware of the possibility of modification 40 in the particular instruments shown by way of example, without departing from the fundamental principles of my invention, I do not intend that the scope of the invention be limited except in accordance with the appended claim.

45 What is claimed is:

A hand operated instrument for removing casings or skins from frankfurters and wieners, said instrument comprising a substantially straight handle of a girth to be firmly gripped by the 50 hand of the user and of such a length as to extend substantially across the entire palm of said user's hand, and a blade secured to the handle and extending from one end thereof, the extending part of said blade having a length less than 55 one-fourth of the handle length and being provided along one edge with teeth and at least the outer one-third of said extending part of the blade being substantially less in width than the width of the handle in the same plane.
